CIGAR CASE

William H. Brooks, P.O. Box 477,
Grass Valley, Nev. 95945

Filed Aug. 11, 1966, Ser. No. 3,433

Term of patent 14 years

(Cl. D85—2)

The essential features of my design for a cigar case are shown in the full line portions thereof, while the cigars shown in broken lines in FIGURE 1 are for illustrative purposes only.

I claim:

The ornamental design for a cigar case, as shown and described.
